UNITED STATES PATENT OFFICE.

JAMES T. WETHERALD, OF BOSTON, MASSACHUSETTS.

DESIGN FOR A SYRINGE-NOZZLE.

SPECIFICATION forming part of Design No. 27,096, dated May 25, 1897.

Application filed March 24, 1897. Serial No. 629,097. Term of patent 7 years.

To all whom it may concern

Be it known that I, JAMES T. WETHERALD, a citizen of the United States, residing in Boston, county of Suffolk, and State of Massachusetts, have invented and produced a new and original Design for a Syringe-Nozzle, of which the following is a specification, reference being made to the accompanying drawings, forming a part thereof.

10 Figure 1 shows a front elevation of my new and original design for a syringe-nozzle, and Fig. 2 a side elevation of the same.

The leading feature of my design consists in the syringe-nozzle of the shape shown, provided with a hole in the conical shield at one side of the pipe and a series of longitudinal grooves along said pipe, all terminating at their lower ends at said hole.

a represents the conical shield; *b*, the pipe projecting therefrom; *c*, a hole at one side 20 of the pipe *b*; *d*, grooves running lengthwise of the pipe *b* at equal distances apart and all terminating at their lower ends at the hole *c*.

I claim—

25 The design for a syringe-nozzle, herein shown and described.

In testimony whereof I have signed my name to this specification in the presence of two subscribing witnesses.

JAMES T. WETHERALD.

Witnesses:

B. J. NOYES,
HARRY O. ROLINSON.
